DESIGN FOR A BRAID

Leo Beer, Kew Gardens, and Herman Stern,
New York, N. Y.

Application October 10, 1945, Serial No. 122,710

Term of patent 7 years

(Cl. D3—32)

To all whom it may concern:

Be it known that we, Leo Beer, a citizen of the United States, and a resident of Kew Gardens, county of Queens, and State of New York, and Herman Stern, a citizen of the United States, and a resident of New York city, county of New York, and State of New York, have invented a new, original, and ornamental Design for a Braid, of which the following is a specification, reference being had to the accompanying drawing, forming part thereof.

The figure is a plan view of a piece of braid showing our new design.

The broken lines outline a design unit, which unit is repeated throughout the length of the braid as indicated.

We claim:

The ornamental design for a braid, substantially as shown and described.

LEO BEER.
HERMAN STERN.
